John R. Lomas

United States Patent Office.

JOHN R. LOMAS, OF NEW HAVEN, CONNECTICUT.

Design No. 2,822, dated November 5, 1867.

DESIGN FOR MELODEON-CASE.

The Schedule referred to in these Letters Patent and making part of the same.

TO ALL WHOM IT MAY CONCERN:

Be it known that I, JOHN R. LOMAS, of the city and county of New Haven, in the State of Connecticut, have invented a new and useful Improvement in Design for Melodeon-Case and Centre-Table; and I do hereby declare that the following is a full, clear, and exact description of the construction and character of the same, reference being had to the accompanying drawing, which makes part of this specification, which drawing is a perspective view of the melodeon-case mounted on a pedestal, the same as is used for a centre-table, showing the lid or leaf open to the key-board, as it will be when playing the melodeon.

I make the melodeon-case in such a shape as to resemble, when closed, the framework and leaf of a quadrilateral centre-table, and mount it on a pedestal, in the same manner as a centre-table, (in such a manner that the treadles for blowing the bellows will not be seen except while in use,) all as fully represented in the drawing.

I make the melodeon-case in all respects to resemble a quadrilateral centre-table, except that I make the lid or leaf in two parts, as represented at A and B, and hang them together with hinges in any of the usual ways, as represented in the drawings. Or I make the lid or leaf in one piece, of wood, marble, or any other suitable material, and fit it to slide to an extent sufficient to expose the key-board, so as to make it convenient to play the melodeon, but so that in either way, when shut, it will fully represent and serve as a quadrilateral centre-table, as plainly indicated in the drawing.

What I claim as my invention, and desire to secure by Letters Patent, is—

The design or configuration of a melodeon-case and centre-table, when constructed and fitted for use, as herein described and set forth in the drawing.

JOHN R. LOMAS.
